US00D970448S

(12) **United States Design Patent** (10) **Patent No.:** **US D970,448 S**
Zhou (45) **Date of Patent:** **** Nov. 22, 2022**

(54) **SOCKET**

(71) Applicant: **Xiaoqin Zhou**, Jurong (CN)

(72) Inventor: **Xiaoqin Zhou**, Jurong (CN)

(**) Term: **15 Years**

(21) Appl. No.: **29/837,880**

(22) Filed: **May 9, 2022**

Related U.S. Application Data

(62) Division of application No. 29/798,249, filed on Jul. 7, 2021, now Pat. No. Des. 957,342.

CLAIM

The ornamental design for a socket, as shown and described.

DESCRIPTION

FIG. 1 is a perspective view of a first embodiment of a socket showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the socket;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines shown in the drawings are for the purpose of illustrating portions of the socket that form no part of the claimed design.

1 Claim, 16 Drawing Sheets
